DESIGN FOR A WASHING MACHINE AGITATOR

Howard Paul Nelligan and Charles C. Scheele,
Syracuse, N. Y., assignors to Easy Washing Ma-
chine Corporation, Syracuse, N. Y., a corpora-
tion of Delaware

Application September 8, 1941, Serial No. 103,223

Term of patent 14 years

To all whom it may concern:

Be it known that we, Howard Paul Nelligan and Charles C. Scheele, citizens of the United States of America, residing in the city of Syracuse, county of Onondaga, and State of New York, have invented a new, original, and ornamental Design for a Washing Machine Agitator, of which the following is a specification, reference being had to the accompanying drawing, forming part thereof.

Figure 1 is a side elevational view of a wash-
ing machine agitator showing our new design;
and

Figure 2 is a top plan view thereof.

We claim:

The ornamental design for a washing machine
agitator, substantially as shown.

H. PAUL NELLIGAN.
CHARLES C. SCHEELE.
